(57) **CLAIM**

The ornamental design for a data processing unit as shown and described.

DESCRIPTION

FIG. 1 is a top front perspective view of a data processing unit.

FIG. 2 is a top back perspective view thereof.

FIG. 3 is a back left bottom perspective view thereof.

FIG. 4 is a back right bottom perspective view thereof.

FIG. 5 is a back bottom perspective view thereof.

FIG. 6 is a front view thereof.

FIG. 7 is a back view thereof.

FIG. 8 is a top view of thereof.

FIG. 9 is a bottom view thereof.

FIG. 10 is a left view thereof; and,

FIG. 11 is a right view thereof.

The broken lines shown in the drawings illustrate portions of the data processing unit that form no part of the claimed design.

1 Claim, 11 Drawing Sheets
